KERF-CUTTING MACHINE

William W. Sloane, Chicago, Ill., assignor to Goodman Manufacturing Company, Chicago, Ill., a corporation of Illinois

Application November 18, 1935, Serial No. 50,295

13 Claims. (Cl. 262—28)

This invention relates to improvements in kerf-cutting machines and more particularly to improvements in kerf-cutting machines of the type adapted to cut an arcuate kerf in a mine wall.

Among the objects of my invention are to provide an improved means of a novel construction for automatically stopping pivotal movement of the cutter bar at certain predetermined points when moving in either direction. Another object of my invention is to so arrange this means as to permit further movement of the cutter bar beyond these predetermined points under manual control, which movement is stopped upon release of the hand from the control means.

Other objects of my invention will appear from time to time as the following specification proceeds.

My invention may be more clearly understood with reference to the accompanying drawings wherein:

20 Figure 1 is a top plan view of the forward portion of a machine embodying the features of my invention with certain parts broken away and shown in section;

25 Figure 2 is an enlarged fragmentary sectional view taken substantially along line 2—2 of Figure 1;

30 Figure 3 is an enlarged detail view illustrating certain details of the clutch shifting mechanism with certain parts shown in longitudinal section;

35 Figure 4 is an enlarged detail view showing certain other of the details of the clutch shifting mechanism not shown in Figure 3; and

Figure 5 is an enlarged detail view illustrating certain details of the automatic mechanism for stopping pivotal movement of the cutter bar.

My invention, as illustrated in the drawings, is shown as being embodied in a track-mounted mining machine of the bottom cutting type of a construction similar to that shown in a prior application, Serial No. 749,345, filed by William T. McCullough, October 22, 1934, which will only herein be shown and described insofar as is necessary to clearly illustrate my present invention.

Said mining machine includes a main frame or truck 10 which forms a base for a turntable 11. Said turntable forms a support and feeding means for a cutting element, generally indicated by reference character 12, which includes a motor 13 having a cutter frame 14 secured thereto and extending forwardly therefrom beyond the forward end of said truck. Said cutter frame is mounted on said turntable on a pair of trunnion supports 15, 15 for adjustment with respect to said turntable about a transverse axis.

5 A frame 16 is supported by the cutter frame 14 for slidable movement with respect thereto in a pair of parallel-spaced guides, generally indicated by reference characters 17, 17. Said frame is adjustably moved toward or from said cutter frame by means of a threaded shaft 17a connected at its lower end to the frame 16 and threaded within the hub of a worm gear 18 journaled in said cutter frame. Said worm gear is selectively driven from the motor 13 by means 10 of a suitable gear train in a manner which will not herein be described since it is no portion of my present invention.

15 The frame 16 forms a pivotal support for a cutter head 19 having a cutter bar 20 projecting therefrom. Said cutter head is mounted in said frame for pivotal movement with respect thereto about an axis perpendicular to the cutting plane of said cutter bar in a suitable manner which will not herein be described since it is no portion 20 of my present invention and is clearly disclosed in the aforementioned prior application of William T. McCullough. Said cutter bar has a cutter chain 21 movable thereabout which is driven from the motor 13 by means of a sprocket 22 and a suitable gear train, generally indicated by reference character 23, but not herein shown or described in detail since it is no portion of my present invention.

25 The means for swinging the cutter bar 20 about the axis of pivotal connection of the cutter head 19 to the frame 16 at either a high positioning speed or a low feeding speed includes a spur gear 24 mounted on the cutter head 19. Said spur gear is meshed with and driven by a spur pinion 25 journaled in the frame 16 and driven by a splined shaft 26. The upper end of said splined shaft slidably engages a splined sleeve 27 driven by a worm gear 28.

30 The worm gear 28 meshes with and is driven by a worm 29 on the forward end of a shaft 30 extending longitudinally of the cutter frame 14 and journaled therein. The pitch of said worm and worm gear is such that said gears will lock said cutter bar from pivotal movement, except 35 when the shaft 30 is driven by the motor.

40 A spur pinion 31 is freely mounted on the shaft 30 adjacent the rearward end thereof. Said spur pinion is journaled on its hub in said cutter frame in a suitable bearing member 32 and is driven from a bevel gear 33 mounted on its hub rearwardly of said bearing member. Said spur pinion forms a drive means for said shaft and its teeth are adapted to be meshed with internal 45 teeth of a clutch member, indicated generally 50 55

by reference character 34. Said clutch member is feathered on the shaft 30 and is slidably moved along said shaft by means of a suitable system of levers in a manner which will not herein be shown or described, since it is no portion of my present invention.

The spur gear 31 also forms a drive member for reduction gearing for driving the shaft at a low feeding speed. Said gearing includes a 10 spur gear 35 keyed to the rearward end of a longitudinally extending shaft 36 and driven by said spur pinion. A spur pinion 37 is keyed to the forward end of said shaft and meshes with and drives a spur gear 38 coaxial with the 15 shaft 36 and journaled on its hub in a bearing member 39 supported in the cutter frame 14.

The shaft 30 is selectively driven from the 20 spur gear 38 by means of the clutch member 34 which is provided with suitable internal teeth 25 adapted to engage external teeth 40 formed on the hub of said spur gear.

The bevel gear 33 is meshed with a bevel 25 pinion 43 on the outer end of a transversely extending shaft 44. A bevel gear 45 is keyed to the opposite end of said shaft and is meshed with and driven by oppositely disposed bevel 30 gears 46, 46 freely mounted on a longitudinally extending shaft 47. Said shaft is journaled in the cutter frame 14 in a suitable manner and 35 the cutter chain drive mechanism 21 is driven from its forward end. Said shaft also forms a drive means for the means for adjustably moving the cutter bar 20 towards or from the frame 14. Said shaft is driven from the motor 13 by 40 means of a gear train, generally indicated by reference character 48.

Suitable clutch mechanisms are provided for 45 selectively connecting either of the bevel gears 46, 46 with the shaft 47 for driving either of said bevel gears therefrom. Said clutch mechanisms may be of any type, but are herein preferably shown as being a pair of friction clutches, generally indicated by reference character 50. Said clutches are of an ordinary construction 50 and are selectively engaged with or disengaged from said shaft by means of a clutch shifting member 51 feathered on said shaft and so arranged that movement thereof in one direction will engage one of said clutches with said shaft 55 and permit said other clutch to be disengaged therefrom (see Figure 3), so that only one of said bevel gears may be driven at a time.

The clutch shifting member 51 has a clutch 60 collar 53 mounted thereon which is adapted to be engaged by a forked member 54 keyed on a transversely extending rock shaft 55. Said rock shaft is pivotally mounted in the cutter frame 14 and has a crank arm 56 secured to its outer end (see Figure 4). Said crank arm has a forked 65 connecting member 57 pivotally connected to its free end which has a rod 58 threaded therein. The opposite end of said rod is in the form of an open eye and is pivotally connected to the outer end of a crank arm 59 mounted on a transversely extending rock shaft 60. Said rock shaft 70 is in turn rocked by means of a suitable hand lever 61 and rocking movement thereof in one direction or another will engage one or the other of the friction clutches 50, 50 with the shaft 47 for swinging the cutter bar 20 in reverse directions without reversal of the motor.

Said hand lever is provided with a spring-pressed plunger 63 adapted to engage a suitable aperture formed in a plate 64 for holding the 75 clutches 50, 50 in a neutral position. Said spring-

pressed plunger is withdrawn from its respective aperture by means of a lever 65 pivoted to said hand lever in an ordinary manner, and is engaged with said aperture by means of a spring 65a interposed between said hand lever and the lever 65. It should be understood that the plate 64 is provided with one aperture only for holding the clutches in a neutral position and that such apertures are not provided for holding said clutches in an engaged position, said clutches 10 being so arranged that they will remain in an engaged position when pressure on said hand lever is released.

Referring now in particular to the novel means for automatically shifting the clutches 50, 50 to 15 a neutral position when the cutter bar 20 reaches a predetermined extreme cutting position when swinging in either direction, a connecting link 66 is pivotally connected to the crank arm 56 and extends forwardly therefrom. Said connecting link has a bifurcated connecting member 67 threaded on its forward end for adjusting the length of said link, which is pivotally connected to the end of a lever arm 68 mounted on a rock shaft 69. Said lever arm is formed integral with an operating lever 70 which has an arm 71 extending radially from the center of said rock shaft in the same direction as the lever arm 68, and another arm 72 extending radially in an opposite direction from the center of said 25 rock shaft. The arm 71 is adapted to be engaged by a lug 73 extending from a shifting member 14 for pivoting said operating lever upon rotation of said shifting member in one direction. The arm 72 is adapted to be engaged by a lug 30 75 for pivoting said operating lever in an opposite direction upon rotation of said shifting member in an opposite direction. It should be noted that when the operating lever 70 is positioned as shown in Figures 2, 4 and 5, that the clutches 40 50, 50 are in a neutral position and that when in this position each of the arms 71 and 72 are engaged by the lugs 73 and 75. Thus, manual shifting of said clutches must be against the shifting member 14, and when either of said 45 clutches is in an engaged position said arms are extended in one direction or another from the axis of the rock shaft 69, dependent upon which of said clutches is in mesh. Said shifting member is rotatably mounted on a vertical shaft 76 50 and yieldably driven thereby at the speed of rotation of said cutter bar.

The drive to the shaft 76 includes a spur gear 77 keyed to the upper end of the sleeve 27 and driven thereby. Said spur gear meshes with and 55 drives a spur gear 78 keyed to the upper end of the vertical shaft 76 for rotatably driving said shaft. Said spur gear is journaled on its hub in a suitable bearing member 79 carried by the cutter frame 14, and the lower end of said vertical shaft is mounted in a suitable bearing member 80 carried by said cutter frame. The reduction between the sleeve 27 and the shaft 76 is such that the speed of rotation of said shaft is the same as the speed of rotation of the cutter 65 bar 20.

The shifting member 14 is yieldably driven from the shaft 76 by means of a driving member 81 feathered on said shaft. Said driving member has a pair of oppositely disposed V-shaped 70 depressions 82, 82 formed therein and adapted to be engaged by V-shaped jaws 83, 83 extending upwardly from said shifting member. The angle of incidence of said depressions with respect to said jaws is such that said jaws may 75

be disengaged therefrom upon a certain predetermined load on said shifting member.

5 A compression spring 84 encircles the hub of said shifting member and abuts the upper surface thereof at one of its ends and is abutted at its other end by a collar 85. Said collar is provided with a plurality of progressively-arranged notches 86, 86 formed on its upper surface. One of said notches is adapted to be engaged by a 10 suitable pin 87 extending through said shaft. It will be apparent that the tension of the spring 84 may be adjusted by rotatably moving the collar 85 to engage the pin 87 with the desired notch 86.

15 It will be apparent from the foregoing description that upon rotation of the cutter bar 20 in one direction, the vertical shaft 76 being driven at the speed of rotation of the cutter bar, the shifting member 74 will be rotatably driven until 20 either the lug 73 or the lug 75 engages the respective lever arm of the operating lever 70, depending upon the direction of rotation of said shifting member. Upon engagement of said operating lever with either the lug 73 or 75, the 25 clutch member 51 will be moved along the shaft 47 by means of the linkage system hereinbefore described, until the spring-pressed plunger 63 engages the aperture in the plate 64 for holding said clutches in a neutral position.

30. When said clutches are in a neutral position and it is desired to pivotally move the cutter bar a further distance in the same direction, it is only necessary to disengage the plunger 63 from the plate and pivot the hand lever 61 against the compression spring 84 and driving member 81, it being apparent that upon engagement of said clutches the shaft 74 may be rotated against said spring and shifting member. The instant the hand is removed from said hand lever, said spring 40 will engage the driving member with the shifting member and throw the clutches 50, 50 to a neutral position. Thus, where the cutter bar is automatically stopped at a certain point, and conditions arise where it is necessary to pivot beyond this point, the cutter bar may be pivoted beyond this point by power as long as hand pressure is exerted against the lever 61, and the instant the hand is removed from said hand lever, the clutches for controlling pivotal movement of said cutter bar will be shifted to a neutral position.

While I have herein shown and described one embodiment of my invention, it will be understood that the construction and arrangement of the various parts may be altered or changed without departing from the spirit or scope of my invention. Furthermore, I do not wish to be construed as limiting myself to the specific form illustrated herein, excepting as it may be particularly limited in the appended claims.

I claim as my invention:

1. In a mining machine, a base, a motor thereon, a frame projecting from said base, a cutter bar pivotally mounted on said frame, means driven by said motor for swinging said cutter bar including a clutch and a vertical shaft selectively driven thereby, and means for automatically stopping swinging movement of said cutter bar at certain predetermined points including a second shaft parallel to said first shaft, a gear mounted on said shaft and rotatably driven by said first shaft, and a member freely mounted on said second shaft and driven by said gear for shifting said clutch to a neutral position.

75 2. In a mining machine, a base, a motor there-

on, a frame projecting from said base, a cutter bar pivotally mounted on said frame, means driven by said motor for swinging said cutter bar including a clutch, and means for automatically stopping swinging movement of said cutter bar at a predetermined point including a member rotatably driven by the means for swinging said cutter bar, and means yieldably driven by said member for shifting said clutch to a neutral position and arranged to permit manual shifting of said clutch against said yieldable driven member.

3. In a mining machine, a base, a motor thereon, a frame projecting from said base, a cutter bar pivotally mounted on said frame, means driven by said motor for swinging said cutter bar including a clutch, and means for automatically stopping swinging movement of said cutter bar at a certain predetermined point including a member rotatably driven by the means for swinging said cutter bar and yieldable means driven by said member for shifting said clutch to a neutral position, and manually operable means acting against said automatic shifting means for shifting said clutch to effect movement of said cutter bar beyond said predetermined positions, said clutch being disengaged by said automatic shifting means upon release of pressure from said manual shifting means.

4. In a mining machine, a base, a motor thereon, a frame projecting from said base, a cutter bar pivotally mounted on said frame, means driven by said motor for swinging said cutter bar in reverse directions without reversal of said motor including a plurality of clutches, manually operable means for shifting said clutches including a rock shaft and means for rocking said rock shaft, and automatic means for shifting said clutches to a neutral position upon movement of said cutter bar to certain predetermined positions when swinging in either direction including a member rotatably driven by the means for swinging said cutter bar, a rocking member having operative connection with said rock shaft, and means driven by said member having operative engagement with said rocking member. 45

5. In a mining machine, a base, a motor thereon, a frame projecting from said base, a cutter bar pivotally mounted on said frame, means driven by said motor for swinging said cutter bar in reverse directions without reversal of said motor including a plurality of clutches, and automatic means for shifting said clutches to a neutral position upon movement of said cutter bar to certain predetermined positions including a member rotatably driven by the means for swinging said cutter bar, a shifting member coaxial with and driven by said member and a rocking member adapted to be engaged by said shifting member, said member having operative connection with said clutches for shifting them to a neutral position upon rocking movement thereof, and means manually operable against said automatic shifting means for shifting either of said clutches to an engaged position to move said cutter bar beyond said predetermined positions, said clutches being disengaged by said automatic shifting means upon release of pressure from said manual shifting means.

6. In a mining machine, a base, a motor thereon, a frame projecting from said base, a cutter bar pivotally mounted on said frame, means driven by said motor for swinging said cutter bar including a clutch, and means for automatically stopping swinging movement of said cutter bar 75

bar at certain predetermined points including a shaft driven by the means for swinging said cutter bar, a member yieldably engaged with said shaft and adapted to be rotated thereby, and 5 clutch shifting means adapted to be engaged by said member.

7. In a mining machine, a base, a motor thereon, a frame projecting from said base, a cutter bar pivotally mounted on said frame, means 10 driven by said motor for swinging said cutter bar including a clutch, and means for automatically stopping swinging movement of said cutter bar at certain predetermined points including a shaft driven by the means for swinging said cutter 15 bar, a member coaxial with said shaft and means driven by said shaft having a yieldable driving connection with said member, and clutch shifting means including a rocking member adapted to be engaged by said member coaxial 20 with said shaft.

8. In a mining machine, a base, a motor thereon, a frame projecting from said base, a cutter bar pivotally mounted on said frame, means driven 25 by said motor for swinging said cutter bar including a clutch, and means for automatically stopping swinging movement of said cutter bar at certain predetermined points including a shaft driven by the means for swinging said cutter bar at the speed of rotation of said cutter bar, a 30 member coaxial with said shaft, and means driven by said shaft having a yieldable driving connection with said member, clutch shifting means including a rocking member adapted to be engaged by said member coaxial with said 35 shaft, and manually operable means for shifting said clutch, said manually operable means being operable against said yieldable driving connection, whereby said cutter bar may be moved beyond said predetermined stopping point under 40 manual control and stopped upon release of said manually operable means.

9. In a mining machine, a base, a motor, a frame, a projecting cutter bar pivotally mounted on said frame, means driven by said motor for 45 swinging said cutter bar in reverse directions without reversal of said motor including reverse gearing and a pair of coaxial clutches, and automatic means for shifting said clutches to a neutral position upon movement of said cutter bar 50 to certain predetermined positions when swinging in either direction including a shaft rotatably driven by the means for swinging said cutter bar at the speed of rotation of said cutter bar, and means yieldably driven by said shaft having operative engagement with said clutches.

10. In a mining machine, a base, a motor, a frame, a projecting cutter bar pivotally mounted on said frame, means driven by said motor for swinging said cutter bar in reverse directions 60 without reversal of said motor including reverse gearing and a pair of coaxial clutches, and automatic means for shifting said clutches to a neutral position upon movement of said cutter bar to certain predetermined positions when swinging 65 in either direction including a shaft rotatably driven by the means for swinging said cutter bar at the speed of rotation of said cutter bar, a member coaxial with said shaft, clutch shifting mechanism, means on said member engageable 70 with said clutch shifting mechanism whereby rotation of said member in one direction will shift one of said clutches to a neutral position and rotation of said member in another direction will shift said opposite clutch to a neutral position,

and a yieldable driving connection between said shaft and member.

11. In a mining machine, a base, a motor, a frame, a projecting cutter bar pivotally mounted on said frame, means driven by said motor for 5 swinging said cutter bar in reverse directions without reversal of said motor including reverse gearing and a pair of coaxial clutches, and automatic means for shifting said clutches to a neutral position upon movement of said cutter bar 10 to certain predetermined positions when swinging in either direction including a shaft rotatably driven by the means for swinging said cutter bar, a member coaxial with said shaft, clutch shifting mechanism, means on said member for engaging 15 said clutch shifting mechanism whereby rotation of said member in one direction will shift one of said clutches to a neutral position and rotation of said member in another direction will shift said opposite clutch to a neutral position, a yieldable driving connection between said shaft and member permitting rotation of said shaft against said member and manually operable means for shifting said clutches against said member.

12. In a mining machine, a base, a motor, a frame, a projecting cutter bar pivotally mounted on said frame, means driven by said motor for swinging said cutter bar in reverse directions 20 without reversal of said motor including reverse gearing and a pair of coaxial clutches, and automatic means for shifting said clutches to a neutral position upon movement of said cutter bar to certain predetermined positions when swinging in either direction including a shaft rotatably 25 driven by the means for swinging said cutter bar at the speed of rotation of said cutter bar, a shifting member coaxial with said shaft, clutch shifting mechanism, means on said shifting member engageable with said clutch shifting mechanism whereby rotation of said shifting member 30 in one direction will shift one of said clutches to a neutral position and rotation of said shifting member in another direction will shift said opposite clutch to a neutral position, a drive member 35 on said shaft and driven therefrom, and yieldable means engaging said drive member with said shifting member for yieldably driving said shifting member.

13. In a mining machine, a base, a motor, a frame, a projecting cutter bar pivotally mounted on said frame, means driven by said motor for swinging said cutter bar in reverse directions 40 without reversal of said motor including reverse gearing and a plurality of coaxial clutches, and automatic means for shifting said clutches 45 to a neutral position upon movement of said cutter bar to certain predetermined positions when swinging in either direction including a shaft rotatably driven by the means for swinging said cutter bar, a shifting member coaxial with said 50 shaft, clutch shifting mechanism, means on said shifting member for engaging said clutch shifting mechanism whereby rotation of said shifting member in one direction will shift one of said clutches to a neutral position and rotation of said shifting member in another direction will shift said opposite clutch to a neutral position, a drive member 55 on said shaft and driven therefrom, and yieldable means engaging said drive member with said shifting member for yieldably driving said shifting member from said drive member and permitting rotation of said shaft, and manually operable means for shifting said 60 clutches against said shifting member.
